UNITED STATES PATENT OFFICE.

HERMANN KURTH, OF MILWAUKEE, WISCONSIN.

IMPROVEMENT IN SEED-SEPARATORS.

Specification forming part of Letters Patent No. 155,736, dated October 6, 1874; application filed September 25, 1874.

To all whom it may concern:

Be it known that I, HERMANN KURTH, of the city and county of Milwaukee and State of Wisconsin, have invented a new and Improved Machine for Cleaning and Separating Grain from Cockle and other impurities; and I do hereby declare that the following is a full, clear, and exact description of the same, reference being had to the accompanying drawings forming part of this specification, in which—

Figure 1 is a plan view; Fig. 2, a longitudinal sectional elevation; Fig. 3, a rear-end view; Fig. 4, detail, showing construction of the friction-wheels; Fig. 5, detail, showing the flat bottom of the cavities in the cylinder; Fig. 6, detail, showing relative arrangement of the brush, slide, chute, and cylinder.

The object of my invention is to provide an improved machine for separating from grain the cockle, garlic, and other impurities contained within the same.

A wooden frame-work has journaled upon it a metallic shaft, which carries at each end a set of double-acting adjustable friction-wheels. Said wheels consist of a hub, having at each end a flange, a detachable disk, fastened to the hub by screws, and an intermediate ring of rubber, forming upon each end of the hub a grooved friction-wheel, whose groove can be adjusted to different sizes. In the grooves of the said wheels, upon each end of the shaft, rest two inwardly-projecting rims of a tapering metallic cylinder, which latter is indented upon its inside with flat-bottomed cavities. Around the outer periphery of said cylinder there is a flat band, upon which guide-rollers attached to the frame run, and keep the cylinder steady. At one end of the cylinder, resting in bearing in the frame, and communicating, through a bevel-gear, with the cylinder-shaft, is a shaft, having an actuating crank and pulley at one end, and a pulley at the other, communicating, through a band, with a parallel shaft below. Said last-mentioned shaft bears an eccentric barrel or cam, which plays in the forked end of a vertical vibrating bar, and the top of said bar is attached to a horizontal slide, which passes through the tapering cylinder, and rests in

guides upon the opposite portions of the frame. To said slide is attached a brush, whose bristles engage with the inner periphery of the cylinder, and brush the impurities from the cavities. At the smaller end of the cylinder is the grain-receiver, which consists of a tray or receptacle having a bottom perforated with small holes to allow the sand and fine particles of foreign matter to fall out, the said bottom being extended in the form of a chute into the cylinder, and perforated therein with holes, which allow the small grain and impurities to pass through into the cylinder. The said tray is provided with sieves constructed, preferably, of sheet metal, and of different-sized perforations, the largest at the top. Above the grain-chute, and attached to the grain-receiver, is a second chute, into which fall the large grains of cockle, garlic, and other impurities, which are precipitated into the same from over the sieves. Said grain-receiver, with its two chutes, is supported at one end upon vertical flat springs attached to the frame and at the opposite end upon horizontal flat springs attached to the opposite end of the frame. To the lower part of the grain-tray are attached adjustable brackets or yokes, and in said brackets revolve cams attached to a shaft that connects with one of the other parallel shafts through a band and pulley, by means of which a vibratory motion is imparted to the grain-receiver and the chutes and the grain-agitator thereon. Inside the cylinder, and inclined to the top chute, are two slides, upon which the impurities drop, and are conveyed away in the said chute. Said slides are pivoted at one end upon adjustable supports, and attached at the other to radially-movable arms pivoted to the frame, and provided with ratchet-teeth and pawls, by means of which the said slides are adjusted in their proximity to the cylinder, and their inclination to the said chute.

My invention consists in the construction and arrangement of the aforementioned devices as combined and presented in the claims.

In the drawings, A represents the frame-work of the machine. B is a shaft journaled in bearings upon the frame, and carrying at each end a set of double-acting adjustable

friction-wheels, C C. Said wheels consist of a hub, D, Fig. 4, which is keyed to the shaft, and provided with flanges *a*, in combination with the disks E and intermediate rings of rubber, all held together by means of the screws G, and forming a pair of grooved friction-wheels, whose grooves may be adjusted to different sizes. In said grooves rest the tapering edges *b* of rims H, attached to the inner ends of a tapering cylinder, I. The said wheels C support the cylinder I, and cause it to revolve by a double-acting frictional contact, the sides of the grooves clasping the edges *b* of the rings H, and holding them tightly while the weight of said cylinder forces the rings down into the grooves, after the manner of wedges. The said cylinder being tapering, one set of these friction-wheels is larger than the other, so as to keep the cylinder on a horizontal axis. Upon the inside of this cylinder I are flat bottom cavities *c*, Figs. 1, 2, and 5, which serve to catch the globular impurities and carry them out of the range of the elongated grains, which latter lose their equilibrium and fall out of the cavities as the cylinder revolves, and pass down the incline through the holes F'. J is a flat band around the cylinder, which moves over the adjustable guide-rollers K, and keeps the cylinder steady. L is a shaft journaled in bearings upon the frame at right angles to shaft B, and connecting therewith through a bevel-gear. Said shaft L carries an actuating-crank and pulley at one end, and a pulley at the other, communicating, through a band, M, with a third shaft, N. Said shaft carries an eccentric barrel or cam, O, which rests in the forked end of a vertical vibrating bar, P, and the top of said bar is attached, through an adjustable connection, to a horizontally-sliding brush, Q, whose bristles engage with the inner periphery of the cylinder, and remove the particles of impurities from the cavities. Said brush Q rests in slides R, which may be adjusted to place the brush tight against the cylinder or away from the same. S is the grain-receiver, which consists of a tray with a finely-perforated bottom, *d*, which is extended in the form of a chute, T, into the cylinder, and is perforated at *e* with holes, which allow the smaller grain and impurities to pass through into the cylinder bottom, the larger grains passing on and being delivered through the holes U. The said grain-receiver S contains sieves *s*, of different-sized perforations, the largest at the top, and are preferably made of perforated sheet metal, because the smooth surface of the same allows the globular-shaped cockle, garlic, &c., to fall over the inclined sieve, while the elongated grains pass through. On a level with the bottom sieve *f* is a second chute, V, just above T, into which the cockle, garlic, &c., are precipitated from the sieves, and carried through the cylinder. The said grain-receiver S and chutes V T are supported at one end upon the vertical flat springs W,

and at the other upon horizontal flat springs X. Y is a fourth shaft, journaled just beneath the grain, which communicates, through a band and pulley, Z, with shaft N. Said shaft has upon it two cams, *g*, which move inside the adjustable brackets or yokes *h*, attached to the lower part of the grain-receiver, and impart to the said receiver and chutes a vibratory motion, by means of which the grain is agitated. Inside the cylinder, and inclined toward the chute V, are the two slides A', which, as the brush removes the impurities from the cavities, receive the same and conduct them into said chute. Said slides are pivoted in adjustable supports B' at one end, and attached to arms C' at the other, which are pivoted to the frame A, and, by means of ratchet-teeth and a pawl, D', control the positions of the slides. The operation of this machine is as follows: The grain is delivered from above to the receiver, which, being agitated, causes the globular-shaped particles of cockle, garlic, and other impurities to be precipitated over the inclined perforated sieves into the chute V, and carried away. The elongated grains pass readily through the graduated sieves until they reach the finely-perforated bottom, when the fine particles of sand, &c., fall through, the grains passing down chute T. As soon as they reach the portion *e* the smaller grain and impurities of the same size pass through into the bottom of the tapering revolving cylinder, and the large grains pass down and are delivered through the holes U in the cylinder. Now, as the cylinder revolves the smaller grains and impurities are caught in the flat bottom cavities in the cylinder, and as the grains are elongated, and the impurities for the most part globular and smaller, the grains fall out and pass down the incline of the tapering barrel, and out through the holes F'. The impurities, being retained in the little pockets or cavities, pass up the side of the cylinder as it revolves, and, when the said cavities are inverted, are emptied upon the slides and conducted away in the chute V along with the first eliminated impurities.

The flat bottom construction of the cavities, as shown in Fig. 5, is intended to retain longer the fine particles of dirt, &c., which are afterward swept down into chute V by the brush Q. The adjustment of the slides A' and the brush Q enable the operator to adapt his machine to the size of the grain, and clean the same more thoroughly of its impurities.

I know that it is not new to construct a revolving cylinder rotated in a suspended position upon friction-wheels, by which it is also actuated. I therefore disclaim the broad idea, and confine myself to my peculiar devices, which possess the following particular advantages: A suspended cylinder having no central axis will not be held steady upon a flat-faced friction-wheel. My device is intended to clutch it on both sides, and hold it as stiffly as though rotated upon a central shaft.

Moreover, by loosening the screw G and widening the grooves, the edges b of the rims H enter the grooves farther, and give a greater amount of frictional contact, and vice versa, thus securing a variable amount of friction.

Having thus described my invention, what I claim as new is—

1. The hub D, with flanges a, the disks E, intermediate rings of rubber F, and screws G, all combined and arranged for the purpose of forming friction-wheels with tapering adjustable groove, substantially as and for the purpose described.

2. The combination of the tapering cylinder I, having tapering rings H and band J, with the friction-wheels C and guide rollers K, substantially as and for the purpose described.

3. The combination, with the cylinder I, of

the reciprocating brush Q, the vertical vibrating bar P, having a forked end, and the eccentric barrel O, substantially as and for the purpose described.

4. The combination, with the cylinder I and chute T, of the inclined slides A', the radially-moving arms C', and the pawls D', substantially as and for the purpose described.

5. The combination, with the revolving tapering cylinder I, of the reciprocating brush Q, the slides A', and the agitated chutes V and T, all contained within the said cylinder, and operating substantially in the manner and for the purpose described.

HERMANN KURTH.
